UNITED STATES PATENT OFFICE.

SOLOMON L. COHEN, OF NEW YORK, N. Y., ASSIGNOR TO THE NEW YORK CONSOLIDATED CARD COMPANY, OF SAME PLACE.

DESIGN FOR A BACK FOR PLAYING-CARDS.

SPECIFICATION forming part of Design No. 20,717, dated May 12, 1891.

Application filed February 12, 1891. Serial No. 381,243. Term of patent 14 years.

To all whom it may concern:

Be it known that I, SOLOMON L. COHEN, a citizen of the United States, and a resident of New York city, in the county of New York and State of New York, have invented and produced a new and original Design for the Backs of Playing-Cards, of which the following is a specification.

The leading feature of my design consists in the representation of Satan, the devil, or Mephistopheles for the backs of playing-cards, and in characteristic foliage ornamentation. In the accompanying illustration and arranged centrally of the card-back are depicted four figures a, impersonating Mephistopheles, the devil, or the "angel of the bottomless pit." These figures are arranged in pairs facing each other, and each pair is reversely arranged, so that whichever end of the card is held uppermost one pair will show in an upright position and be clearly discernible. Each figure consists of a head and a body having a bushy or feathery appendage, and each carries a pitchfork b, which extends to near the marginal edge of the card. The figures are surrounded by foliage-like or scalloped ornamentation c, which terminates at the corners of the card and at intermediate points in scrolls or convolutions.

What I claim is--

The design for the backs of playing-cards, substantially as shown and described.

Signed at New York city, in the county of New York and State of New York, this 11th day of February, A. D. 1891.

SOL. L. COHEN.
